US0D1071046S

(12) **United States Design Patent** (10) **Patent No.:** **US D1,071,046 S**
(45) **Date of Patent:** **** Apr. 15, 2025**

(54) **ATHLETIC BALANCE CONTROL
PLATFORM WITH PNEUMATIC
ACTUATION**

(71) Applicant: **University of Tennessee Research Foundation**, Knoxville, TN (US)

(72) Inventor: **Erkan Kaplanoglu**, Knoxville, TN (US)

(73) Assignee: **University of Tennessee Research Foundation**, Knoxville, TN (US)

(**) Term: **15 Years**

(21) Appl. No.: **29/884,368**

(22) Filed: **Feb. 10, 2023**

(51) LOC (15) Cl. **21-02**

(52) U.S. Cl.

(57) **CLAIM**

The ornamental design for an athletic balance control platform with pneumatic actuation, as shown and described.

DESCRIPTION

FIG. 1 is a perspective view of an athletic balance control platform with pneumatic actuation; FIG. 2 is a front view thereof;

FIG. 3 is a rear view thereof;

FIG. 4 is a leftside view thereof;

FIG. 5 is a rightside view thereof;

FIG. 6 is a top view thereof; and,

FIG. 7 is a bottom view thereof.

The broken lines in the drawings illustrate portions of the athletic balance control platform with pneumatic actuation that form no part of the claimed design.

1 Claim, 4 Drawing Sheets
